UNITED STATES PATENT OFFICE.

PHILIP CHARLES LAWLESS, OF HAMPSTEAD HEATH, LONDON, ENGLAND.

FLEXIBLE RULER.

No. 806,546.

Specification of Letters Patent.

Patented Dec. 5, 1905.

Application filed September 30, 1904. Serial No. 226,713.

To all whom it may concern:

Be it known that I, PHILIP CHARLES LAWLESS, a subject of the King of Great Britain and Ireland, residing at 50 Parliament Hill, 5 Hampstead Heath, London, England, have invented new and useful Improvements in Flexible Rulers, of which the following is a specification.

My invention relates to the class of flexible rulers usually made of flat strips of resilient sheet metal or vulcanite, to which is secured a facing of india-rubber on one or each of its sides. Hitherto the frequent bending of the ruler has in course of time caused the india-rubber to separate from the metal or vulcanite; and the object of the present invention is to provide a ruler wherein this separation shall be entirely prevented and which, as compared with flexible rulers hitherto used, 20 shall be of cheaper construction. I attain this object by the arrangements illustrated in the accompanying drawings, in which—

Figure 1 is a plan, and Fig. 2 an edge, view of one construction of the improved ruler, 25 both of these views being partly broken away. Figs. 3 and 4 are elevations of the respectively opposite ends of the ruler shown in Figs. 1 and 2.

Instead of the before-mentioned facings 30 being in the form of flat sheet or strip rubber and riveted, cemented, or otherwise secured to the ruler, as heretofore, they are in the form of rubber or equivalent cord, as in Figs. 1, 2, 3, and 4, and rely for their fixation upon 35 their penetrating the ruler, such penetration entirely superseding the above-named means hitherto relied upon.

In the arrangements shown in the draw-

ings the rubber cord 1 is threaded alternately from one side to the other of the ruler 2 40 through series or rows of perforations 3 in the said ruler, the meeting ends 4 of the cord 1 being secured by being tightly squeezed through a single perforation. If desired, the edge of this last-named perforation may be 45 burred over or flanged, or the said perforation may have an eyelet secured therein to prevent the rubber cord being chafed or cut by such edge.

The rubber cord 1 may be either in a single piece, as shown in the drawings, or in two or more pieces, the meeting ends being secured in the same manner as above described.

By the before-described arrangement the india-rubber is securely held to the ruler and 55 provides a very satisfactory support for holding the ruler out of contact with the surface to be ruled and allows the ruler to be freely bent backward and forward without disturbing the connection between the rubber and 60 ruler.

What I claim as my invention, and desire to secure by Letters Patent, is—

In a flexible ruler, the combination of a flexible strip of resilient sheet material having 65 perforations distributed along its length, and cord threaded alternately in opposite directions through the perforations.

In testimony whereof I have signed my name to this specification in the presence of 70 two subscribing witnesses.

PHILIP CHARLES LAWLESS.
